UNITED STATES PATENT OFFICE.

CLINTON S. MILLER AND JOHN E. DU BOIS, OF TIFFIN, OHIO.

REFRIGERATOR-CAR.

SPECIFICATION forming part of Letters Patent No. 520,442, dated May 29, 1894.

Application filed March 25, 1893. Serial No. 467,557. (No model.)

To all whom it may concern:

Be it known that we, CLINTON S. MILLER and JOHN E. DU BOIS, citizens of the United States, residing at Tiffin, in the county of Seneca and State of Ohio, have invented a new and useful Refrigerator-Car, of which the following is a specification.

Our invention relates to refrigerator cars, and refers particularly to mechanism for operating a pump whereby the refrigerating pipes are supplied with the fluid from the tank.

The object of our invention is to provide a simple, inexpensive and effective mechanism which can be applied to any ordinary car, in present use, without altering or adapting the construction of the latter.

A further object of our invention is to provide an operating mechanism which derives its power from the axle of the car, and which can be disconnected from such source of power without entering or opening the car.

Further objects and advantages of our invention will appear in the following description and the novel features thereof will be particularly pointed out in the appended claim.

In the drawings:—Figure 1 is a perspective view of a refrigerator car embodying our invention. Fig. 2 is a longitudinal sectional view of the same. Fig. 3 is a detail view of the movable pulley. Fig. 4 is a similar view of the fixed pulley. Fig. 5 is a similar view of the supporting lever.

Like numerals denote corresponding parts throughout the several views.

1 designates the body of the car, 2 the ordinary truck, 3 one of the axles carried by said truck, 4 an ordinary priming tank, 5 the refrigerating coils or pipes, and 6 a pump which may be of any preferred construction, connected to said tank and to the coils or pipes to produce, when in motion, a circulation of the refrigerating fluid.

7 represents a divided sectional friction pulley or roll, the same being halved to form the duplicate superposed semicircular sections 8 which are provided with integral off-standing collar portions projected from both sides

50 and having clutches 9 to engage the axle 3.

These clutches consist, as shown in the drawings, of duplicate perforated flanges or ears which are connected, when in place upon the axle, by the fastening bolts 10, and have their outer edges disposed in a line flush with the 55 periphery of the roll. The friction pulley or roll 7, which for convenience we have termed the fixed pulley or roll, is thus fastened securely upon the axle and turns therewith, and the same may be secured as described to any 60 car axle in use.

11 represents the movable friction pulley or roll which is so mounted as to normally bear in contact with the surface of the fixed pulley or roll and rotate therewith, and 12 65 represents a pitman which is pivotally connected to this movable pulley or roll and to the piston-rod 13 of the above mentioned pump, whereby the rotation of the pulley 11 is communicated through said pitman to the 70 pump.

The truck of a railway car in motion is continually rocking and the body of the car is vibrating vertically in relation thereto, and as it is necessary in the carrying out of our 75 invention to provide means to preserve an even and constant pressure and contact between the movable and fixed friction pulleys or rolls, we employ a tension device constructed as follows: 14 represents a bell-crank supporting lever, one of whose arms, 15, is approximately horizontal in position, and is provided at its terminal with a bearing 16 for the spindle 17 of the pulley or roll 11. The other, approximately vertical, arm 18 of the 80 supporting lever is provided with an eye 19. The supporting lever is pivotally connected to a stationary part of the body of the car at the angle between its arms, as shown at 20.

21 represents a stem which extends through 90 the eye 19 at the free terminal of the arm 18 of the supporting-lever, is provided at its inner end with a head 22 to engage said eye, and extends outwardly through the casing of the car. Upon this stem is arranged a coiled 95 spring 23 which bearing against the free end of the arm 18, normally holds the movable pulley or roll in contact with the fixed pulley or roll.

Connected to the free outer end of the stem 100

21 is a cam-lever 24, by means of which the stem may be drawn outward, thereby drawing the upper arm of the supporting-lever in the same direction and raising the movable 5 friction roll from contact with the fixed roll.

It will be seen from the above description that the contact between the friction rolls will be preserved at all times, even although the truck and car-body rock and roll in a manner common to such parts, and therefore the pump will be operated steadily during the motion of the car. Furthermore, the motion of the pump may be checked at any time without opening the car; by the manipulation of 15 the cam-lever.

Goods which are not perishable and therefore do not need refrigeration may be shipped in a car equipped with our improved mechanism, it being simply necessary to disconnect 20 the friction rolls by the operation of the cam-lever as described.

It will be plain to those skilled in this art that our improved mechanism for operating the pump may be attached readily, quickly, 25 and cheaply to any car now in use, and as changes in form, proportion, and minor details of construction may be resorted to without departing from the spirit or sacrificing the advantages of our invention, we reserve 30 the right to make such alterations within the scope of our invention.

It will be apparent, furthermore, that our improved means for operating the pump for forcing the refrigerating fluid through the 35 distributing tubes will operate with equal effect when the car is moving in either direction. The direction in which the car is moving does not affect the operation of the parts.

The liquid which we propose to employ in 40 connection with our refrigerating device is composed of carbonate of ammonia and sodium hypo-sulphite, the said combination producing a liquid which is incongealable. Any suitable or approved means may be em-

ployed to preserve the refrigerating liquid at 45 the desired temperature.

A suitable thermostat may be employed in connection with the car in order to preserve an even temperature whereby fruits and vegetables may be transported in a temperature 50 corresponding with that in which they were grown, and thus preventing drying and wilting while on the way.

It will be understood that changes in the form, proportion and minor details of the construction of our device may be resorted to without departing from the spirit or sacrificing any of the advantages of our invention.

Having thus described our invention, what we claim, and desire to secure by Letters Patent of the United States, is—

The combination with a box-car having a friction roll on one of its axles, and a refrigerating apparatus mounted within the car and having an upright distributing pump, 65 with its piston rod moving there-below; of a suitably mounted bell-crank lever provided at one end with a bearing block, a movable friction pulley disposed directly under the pump and having a spindle journaled in the 70 lever bearing block, a pitman pivoted to one side of the movable friction pulley and to the pump piston rod, an operating stem or link connected to the free end of the bell-crank lever, a cam lever pivoted to the outer end of 75 said stem outside of the car-body, and a spring coiled on said stem and normally pressing against one end of said bell-crank lever, substantially as and for the purpose described.

In testimony that we claim the foregoing as 80 our own we have hereto affixed our signatures in the presence of two witnesses.

CLINTON S. MILLER.
JOHN E. DU BOIS.
